Edwin S. Lenox
Inventor.

UNITED STATES PATENT OFFICE.

EDWIN S. LENOX, OF WORCESTER, MASSACHUSETTS, ASSIGNOR TO WASH-BURN & MOEN MANUFACTURING COMPANY, OF SAME PLACE.

WIRE BALE-BAND.

SPECIFICATION forming part of Letters Patent No. 230,790, dated August 3, 1880.

Application filed April 7, 1880. (Model.)

To all whom it may concern:

Be it known that I, EDWIN S. LENOX, of Worcester, in the county of Worcester and State of Massachusetts, have invented a new and useful Improvement in Wire Bale-Bands and their Connecting-Pieces, which improvement is fully described in the following specification and accompanying drawings, in which—

10 Figure 1 represents a perspective view of my improved bale-band when its ends are united or secured at near the greatest length allowed by the connecting-piece. Fig. 2 is a longitudinal sectional elevation of the same, 15 illustrating the bale-band with its ends connected and adjusted for a shorter length. Fig. 3 is a horizontal view of a modification of the connecting-piece. Fig. 4 represents a view of the yoke end of the connecting-piece. 20 My invention relates to a wire bale-band having a connecting-piece, by which the ends of the said band may be connected at different points, either farther from or nearer together, or overlap or pass each other for making the 25 band substantially longer or shorter, as may be required.

The object of my invention is to produce a wire bale-band which will be readily adjustable in length by means of the connecting-piece 30 employed, whereby the same band may be made to have a length adapted to be applied to varying sized bales.

In the drawings, A A A represent the bale-band, made of wire and formed of strands *a a*, 35 and having their ends terminating with loops *a'* and *a''*. B B are braces, one or more, used to keep the strands *a* separated. The said braces may be made of any form of construction that will be adapted to hold said strands 40 apart.

C is the connecting-piece, provided with projecting catches *c c* and *c' c'*, arranged on the opposite sides or edges, as shown. Made with one end of the said connecting-piece is the 45 yoke *d*, having its ends provided with openings or holes *x x*, as shown in Figs. 1 and 4, for receiving the strands *a a* of one of the loop ends of the band, as shown in Fig. 1. With the opposite end of the connecting-piece is made the 50 brace *g*, against the projecting ends of which

the strands of the opposite end loop bear to prevent the tilting of the connecting-piece.

It will be observed that by my improvement the loop end *a'* of the band may be connected to the connecting-piece C by any one of the 55 catches *c*, whether it be the first or second catch from the yoke end *d* or brace end *g*, or any of the intermediate catches, while the loop end *a''* may be connected to any one of the catches *c'* in the same manner.

It will also be observed that when the loop end *a'* is connected by the first catch *c* nearest to yoke *d* and the loop end *a''* is connected by the first catch *c'* the length of the band will be adjusted with its longest length of 65 brace for encircling a bale, while when the loop end *a'* is made to engage with one of the catches *c* nearer the brace *g* of the connecting-piece and the loop end *a''* with one of the catches *c'* nearer the yoke *d* the bale-band 70 will be adjusted with a shorter length for encircling a bale of smaller circumference, while when the said loop ends are made to engage with the catches *c* and *c'* at near the center of 75 length of the connecting-piece the length of the band will be of a medium extension.

It will also be readily seen that by the use of the connecting-piece C, made with several catches, *c* and *c'*, a single-strand wire bale-band furnished with long loops *a'* and *a''* at its 80 ends will be well adapted to give an extension or contraction of length of the band when connected to adapt its use to bales of varying circumferences, as when made with strands, as shown, while it may also be readily seen 85 that when the catches are arranged at the side edges of the connecting-piece, as shown in Fig. 3, the extension or contraction of the length of the band will also be had.

Having described my invention, what I 90 claim, and desire to secure by Letters Patent, is—

1. A wire bale-band provided with the connecting device C, all made and operated substantially as shown and set forth.

2. The combination, with the connecting-piece C, of two or more catches *c* and two or more catches *c'*, each said series of catches being so arranged as to be in opposition with each other to produce varying distances be- 100

tween said opposing catches, substantially as shown and set forth.

3. A wire bale-band provided with a connecting-piece so constructed that the loops of said band can be secured either nearer to or farther from each other by said connecting-piece, substantially as set forth, for the purpose specified.

4. The combination, with the connecting-piece provided with catches *c* and *c'*, of the yoke *d*, substantially as shown and set forth.

5. The combination, with the connecting-piece provided with catches *c* and *c'*, of the brace *g*, substantially as shown and set forth.

6. The combination, with the strands *a a*, ¹⁵ two or more, of brace *B*, one or more, substantially as shown and set forth.

EDWIN S. LENOX.
